UNITED STATES PATENT OFFICE.

LEONARD HARRIS, OF LONDON, ENGLAND.

MANUFACTURE OF PNEUMATIC CUSHIONING DEVICES FOR THE ELASTIC SUSPENSION
OF ROAD-VEHICLES.

1,083,810.

Specification of Letters Patent. Patented July 16, 1912.

Application filed June 17, 1911. Serial No. 634,183.

To all whom it may concern:

Be it known that I, LEONARD HARRIS, a subject of the King of Great Britain, residing in London, England, have invented 5 certain new and useful Improvements in the Manufacture or Construction of Pneumatic Cushioning Devices for the Elastic Suspension of Road-Vehicles, and of which the following is a specification.

10 I have before proposed to employ certain pneumatic cushions which were to be fitted between the wheel axles and the body of the vehicle, and such cushions consisted of a casing of flexible and inextensible material, 15 such as rubber and fabric, of approximately spherical or globular form, but open at the top and bottom, and around the annular edges of such openings the casing was to be provided with means by which it could be 20 engaged with upper and lower cup-like members secured to the respective parts which were to be insulated from one another as regards vibration. Such pneumatic cushioning devices were fitted with a valve by 25 which they could be inflated, or contained an inner elastic case of india rubber, fitted with a valve which extended to the exterior.

Reference is made to my specification forming part of United States Patent No. 36 783,833, dated Feb. 28, 1905, for "Antivibration pneumatic cushion."

The present invention consists in the method or process by which a flexible and non-extensible casing for the purposes above 35 enumerated, is manufactured, as hereinafter particularly described and claimed.

According to this invention the approximately spherical casing aforesaid is composed of an inner lining of suitable thin 40 material, such as india rubber, a winding of string thereon coated with india rubber or the like, and an exterior thickness of india rubber or the like having ribs around the annular edges of the two diametrically opposite 45 openings, all vulcanized together.

The process of manufacture of the casing according to this invention consists in applying a cover of suitable thin lining material, such as india rubber, around a core, 50 then winding a length of string having a vulcanizable adhesive coating of india rubber or the like over such cover, then placing the structure in a mold, then inserting india rubber to fill such mold around such string.

covered structure, then vulcanizing the 55 whole, afterward removing the structure from said mold, and finally removing the said core from the said flexible and non-extensible casing.

The term "string" is intended to include 60 cord, tape, wire or the like, of any suitable material, such as silk, cotton, linen, hemp, metal or equivalent substances.

The invention is hereinafter more fully 65 described with reference to the accompanying drawings, in which—

Figure 1 is a sectional elevation of a casing, in which the string is wound in the form of a helix around the core from top to bottom thereof or vice versa. Fig. 2 is a 70 plan of the lower portion of the mold, showing the core in position and the molded casing in section. Fig. 3 illustrates another method of winding the string upon the core. Fig. 4 is a section through a molded casing 75 and a core, constructed to enable the string to be wound in a longitudinal direction over the said core.

Upon a suitable sectional core 1 such as is shown in Figs. 2 and 4, there is applied a 80 cover 2 of thin material—say india rubber—suitable to form the lining of the casing, and upon this cover is wound the string 3. This string, which is in a continuous length, may be wound, as shown in Figs. 1 and 2, in a 85 helical direction around the core, or as shown in Fig. 3 it may be wound around the core at an angle to its axis, and when the core has been sufficiently covered by winding 90 the string in one direction, the direction of winding is then changed so that the string last applied crosses that previously wound upon the core, and forms a cross winding as shown. The core 1 being thus prepared, it is placed within the mold 4 and india rubber or like vulcanizable body material 5 molded on to the string surrounding the said core to the shape of the interior of the mold, the said body material becoming incorporated 95 with the string 3, so that the string becomes 100 integral with the body material and is vulcanized therewith as well as to the lining 2.

The core 1 is constructed in any convenient or well known manner so that when the casing is removed from the mold, the center 105 for example of the core can be first removed, after which its other sectional parts can be withdrawn through the aperture at

either end of the casing previously occupied by the center of said core.

Fig. 4 shows a form of core adapted for the winding of the string in a continuous length in a longitudinal direction. For this purpose there is provided a hollow central member 7, around which are assembled the sections 8 completing the core. When the core, excepting its axis 9, has been assembled and the lining 2 placed thereover, the continuous string 3 is wound so as to extend in a longitudinal direction thereon, the string, after passing over the lining upon the outside of the core, being threaded 15 through the hollow member 7, again passed over the lining upon the outside of the core, and so on until sufficient string is employed to form the desired reinforcement. The core having thus been prepared, the axis 20 9 is passed through the hollow member 7, and the core placed in the mold as described with reference to Fig. 2. After the molded casing 2, 3, 5, Fig. 4, together with the mold core 7 is removed from the mold and the axis 25 9 withdrawn, the string 3 is cut at the points where it enters the hollow core at each end thereof, so that the hollow member 7 of the said core can be removed from the center of the casing and the core sections 8 30 withdrawn through the aperture at either end of the said casing, the casing then being ready for use.

For the purpose of strengthening the annular ribs or beadings 10 formed at the upper and lower ends of the said casing, and to prevent the wear of the said beads consequent upon any slight friction which might be caused between the beads and the cuplike members by which the casing is retained in position on the vehicle, a layer of canvas or the like can be applied on the external surface of the said upper and lower beads.

In order that the string, when applied to the core in the desired manner, shall be retained in position thereon until the india rubber is molded to complete the casing, the said string is preferably treated by coating it with an india rubber or like vulcanizable adhesive solution, prior to, or during the winding thereof on to the core, or the core covering or casing lining 2 may be treated with india rubber or like solution before the winding process.

55 The term "india rubber" as hereinafter employed is intended to include alternatively other like vulcanizable material as mentioned in the foregoing description.

60 What I claim as my invention and desire to secure by patent is:

1. The within described process of manufacturing a flexible and practically non-extensible casing of approximately spherical form, having two diametrically opposite 65 openings at the top and bottom, and hav-

ing ribs around the annular edges of such openings adapted to engage upper and lower cup-like members, said casing being for use in pneumatic cushioning devices to be located between the wheel axles and the bodies of road vehicles; said process consisting in applying a thin lining for the casing of india rubber around a suitable core, then winding a length of strain-resisting string over such lining and simultaneously attaching the same thereto by an adhesive coating of india rubber, then placing the structure in a mold, then filling such mold with india rubber for an outer thickness including said ribs around said string-covered structure, 70 then vulcanizing the casing as a whole, afterward removing the structure from the mold, and finally removing the core from the flexible and non-extensible casing. 75

2. In the process of manufacturing a flexible and practically non-extensible casing of approximately spherical form, having two diametrically opposite openings at top and bottom, and having ribs around the annular edges of such openings adapted to engage upper and lower cup-like members, said casing being for use in pneumatic cushioning devices to be located between the wheel axles and the bodies of road vehicles; the method of introducing a continuous reinforcing string consisting in applying a thin lining for the casing around a suitable core, 80 and then winding a continuous length of string coated with adhesive india rubber over such lining before filling the mold with the india rubber for the outer thickness of the casing including said ribs, the whole being adapted to be vulcanized at one operation, whereby said string is made substantially integral with said outer thickness of 85 the india rubber. 90

3. The within described process of manufacturing a flexible and practically non-extensible casing of approximately spherical form having two diametrically opposite openings at top and bottom and having ribs around the annular edges of such openings adapted to engage upper and lower cup-like members, said casing being for use in pneumatic cushioning devices to be located between the wheel-axles and the bodies of road vehicles; said process consisting in applying a thin lining for the casing, of india rubber, around a core having separable sections assembled around a hollow central member, 110 then winding a length of string upon said lining, said string passing through said hollow central member and over the exterior of said lining, then placing a spindle through said hollow member of said core and placing 115 the said string-covered structure into a mold, then inserting india rubber for the outer thickness of the casing into said mold and around said string-covered structure, then vulcanizing the india rubber as a 120 125 130

1,033,010

whole, then removing the structure from the mold, then cutting the string around said openings, and finally removing the core from the flexible and non-extensible casing.

5 The foregoing specification of my improvements in the manufacture or construction of pneumatic cushioning devices for the

elastic suspension of road vehicles signed by me this first day of June 1911.

LEONARD HARRIS.
